UNITED STATES PATENT OFFICE

2,576,276

APPARATUS FOR MAKING FLOCK COVERED PAPER

Orion William Berglund, Dayton, Ohio, assignor
to The Commonwealth Engineering Company
of Ohio, Dayton, Ohio, a corporation of Ohio

Application August 2, 1948, Serial No. 41,992

4 Claims. (Cl. 91—8)

1

This invention deals with a flock-covered sheet material and the process and apparatus for making such material.

It is an object of this invention to provide a sheet material that is characterized by high tensile strength.

It is another object of this invention to provide a combination sheet material in an extremely inexpensive and simple manner.

It is still another object of this invention to provide a sheet material which has a very pleasing and decorative appearance.

It is still another object of this invention to provide a sheet material which has a good grip so that slipping is prevented.

It is still another object of this invention to provide a sheet material which is free from tackiness so that it can be stored in multiple layers, for instance, it can be wound on reels or piled in stacks.

These and other objects are accomplished by depositing a flock material onto a temporary base while applying suction thereto, thereafter superposing a sheet with an adhesive surface as the permanent base over said flock-covered temporary base whereby said flock is transferred to said permanent base, removing said flock-covered permanent base from said temporary base, and subjecting it to drying.

While various kinds of materials are suitable for the temporary base, a 100-mesh metal screen and a cloth consisting of vinyl chloride-vinyl acetate copolymer have been found especially satisfactory.

As the permanent base, fabric, leather, plastics and the like are operative; however, paper, especially when impregnated and/or coated with an adhesive material, is preferred, since it is the least expensive material and yet yields a final product of excellent characteristics.

As the impregnant or coating composition, all kinds of resinous solutions are satisfactory; for instance, a vinyl resin dissolved in cyclohexane or a polystyrene resin dissolved in carbon tetrachloride have been used with good results. Alkyd paints and varnishes and nitrocellulose containing solutions have also been found satisfactory. While the adhesive material may be used in the form of a coating and/or of impregnation, the method is still more simplified by solely using a sheet of adhesive properties as the permanent base, such as a sheet of plastic material the surface layer of which is partly dissolved and thus tacky enough to bond the flock.

Likewise, the material of the flock is not criti-

2

cal. Rayon, cotton, wool, paper and asbestos flock have been used and found suitable. In order to give the final product a more decorative effect, flock of different colors may be used. If paper, for instance, is covered with asbestos flock on both its surfaces, a flame resistant product is obtained.

The end product has a suede leather-like appearance and, since the tensile strength is relatively high due to the impregnation by a resin, or the like, the material may be satisfactorily used as a leather substitute.

It has also been noticed that if a screen with a pattern is used, this pattern is transferred by the flock to the permanent base so that in case a patterned product is obtained.

In the following description taken in connection with the accompanying drawings two embodiments of my invention are described. This description is not given for the purpose of limitation, but merely for that of illustration.

In these drawings:

Figure 1 is a diagrammatic elevational view of an apparatus for carrying out my invention; and

Figure 2 is a diagrammatic elevational view of another embodiment of my invention.

Referring to the drawings in detail, and in particular to Figure 1, the reference numeral 10 designates an endless belt consisting of a metal screen. This endless belt is driven by two wheels 11 and 12. A suction box 13 operated by a suction pump 14 is arranged under said belt, and a casing 15 is arranged above that belt so as to concentrate the suction effect. A flock dispenser 16 containing flock 17 is mounted above said casing 15; it applies the flock 17 in a layer 18 to the screen 10. Due to the suction exerted, the individual fibers of the flock assume an upright position which is responsible for the velvet or suede-like appearance of the final product. A reel 19 carries and dispenses sheet material 20 intended as the permanent base for the flock. A nozzle 21 applies an adhesive material 22 onto said sheet material 20. The thus treated sheet designated with the numeral 25 is led over two guide rolls 23 and 24 and then brought in contact with the flock layer 18 on the screen 10. The flock is immediately transferred to and held by the sheet 25. An infra-red lamp 26 provides for the heat necessary for drying the material whereupon it can be wound on a reel 27.

The embodiment illustrated in Figure 2 differs from that just discussed in that one material is used for both purposes, namely as the permanent base and as the adhesive. In this

Likewise, the material of the flock is not criti-

embodiment, like in that of Figure 1, a screen belt 28 is driven by two drive rolls 29 and 30, and a suction box 31 with a pump 32 is arranged below said belt whereas a casing 33 is mounted above said belt and said suction box. A hopper 34 furnishes flock 35 in the form of a layer 36. A funnel 37 with an adjustable opening 46 dispenses a film forming material 38. This material is spread onto the screen 28 by means of a vibrator roll 39 and a spreader roll 40, and its thickness is equalized and adjusted by means of a doctor blade 42 which is adjustable by means of a screw device 43. The film 41 is subjected to a drying step by means of an infra-red lamp 44 and then removed from the screen 28. The final product obtained thereby comprises the plastic film 41 carrying on the under-side the layer of flock 36. As in the embodiment shown in Figure 1, the finished product is wound on a reel 45.

It will be understood that the process of this invention may also be carried out in a discontinuous manner.

It has been found advantageous in some instances to operate in an electrostatic field whereby the vertical position of the flock is maintained and guaranteed in the final product.

There are many uses for this invention. As has been mentioned above, the material is an excellent and inexpensive leather substitute; moreover, the invention is very valuable for manufacturing oilcloth.

It will be understood that while there have been described herein certain embodiments of my invention, it is not intended thereby to have the invention limited to the specific details given, since this invention is susceptible to various modifications and changes which come within the spirit of the disclosure and the scope of the appended claims.

I claim;

1. A device for manufacturing a flock-covered sheet material in a continuous operation, comprising a flock dispensing means having a closed casing portion; a metal screen adjacent said casing portion for temporarily receiving said flock and conveying the same through a given path; suction means to apply suction to said flock over a portion of the said given path; means including said receiving means to remove said suction means from said flock on said receiving means; a means for depositing a sheet with an adhesive surface onto said flock after removing said suction means, whereby said flock is transferred to and held by said adhesive surface; a means for removing said flock-covered sheet from said receiving means; and means for drying said flock-covered sheet.

2. A device for manufacturing a flock-covered sheet material in a continuous operation, comprising a flock dispensing means having a closed casing portion; a cloth sheet consisting of vinyl chloride-vinyl acetate copolymer for temporarily receiving said flock and conveying the same through a given path; suction means to apply suction to said flock over a portion of the said

given path; means including said receiving means to remove said suction means from said flock on said receiving means; a means for depositing a sheet with an adhesive surface onto said flock after removing said suction means, whereby said flock is transferred to and held by said adhesive surface; a means for removing said

10. 3. A device for manufacturing a flock-covered sheet from said receiving means; and means for drying said flock-covered sheet.

10 3. A device for manufacturing a flock-covered sheet material in a continuous operation, comprising a flock dispensing means having a closed casing portion; an endless screen belt adjacent said casing portion for temporarily receiving said flock and conveying the same through a given path, said belt having a pattern on its surface; suction means to apply suction to said flock over a portion of the said given path; means including said belt to remove said suction means from said flock; a means for depositing a sheet with an adhesive surface onto said flock after removal

15

20

an adhesive surface onto said flock after removing said suction means, whereby said flock is transferred to and held by said adhesive surface; a means for removing said flock-covered sheet from said receiving means; and means for drying said flock-covered sheet.

4. A device for manufacturing a flock-covered sheet material, comprising a flock-dispensing means having a closed casing portion; a foraminous belt for temporarily receiving said flock from said casing portion; a suction device arranged under said belt to apply suction to said flock on said belt; means for removing said suction from said flock on said belt; a means for depositing a sheet with an adhesive surface onto said flock after removing said suction from said flock on said belt, whereby said flock is transferred to and held by said adhesive surface; a means for removing said flock-covered sheet from said receiving means; and means for drying said flock-covered sheet.
